Minn.

Primary Examiner—Lucy Lieberman
Attorney, Agent, or Firm—Fish & Richardson P.C.

[73] Assignee: **Reckitt & Colman Inc.**, Wayne, N.J.

[57] **CLAIM**
The ornamental design for an upper shoulder, neck, and cap of a bottle, as shown and described.

[**] Term: **14 Years**

DESCRIPTION

[21] Appl. No.: **55,522**

[22] Filed: **Jun. 6, 1996**

Related U.S. Application Data

[63] Continuation of Ser. No. 34,931, Feb. 9, 1995, abandoned,
Division of Ser. No. 14,016, Oct. 8, 1993.

FIG. 1 is a front elevation of an upper shoulder, neck, and cap of bottle showing our new design, the rear elevation
being a mirror image thereof except for the conventional
screw threading on the bottle neck;

[51] **LOC (6) Cl. 09-01**

FIG. 2 is a right side elevation thereof, the left side elevation
is a mirror image thereof except for the conventional screw
threading on the neck; and,

[52] **U.S. Cl. D9/542; D9/454**

FIG. 3 is a top plan view thereof.

[58] **Field of Search** D9/338, 542, 543,
D9/454, 445, 436, 447, 449; 215/382, 41,
383, 384; 401/202

The broken line environmental showing is for illustrative
purposes only and does not form part of the claimed design.
